UNITED STATES PATENT OFFICE.

HENRY COLLIER SMITH, OF ST. MARYS, OHIO, ASSIGNOR TO THE QUICKWORK COMPANY, OF ST. MARYS, OHIO, A CORPORATION OF OHIO.

RIBBING AND PERFORATING MACHINE.

Application filed May 16, 1924. Serial No. 713,722.

To all whom it may concern:

Be it known that I, HENRY COLLIER SMITH, a citizen of the United States, and residing at St. Marys, in the county of Aut-glaize and State of Ohio, have invented a new and Improved Ribbing and Perforating Machine, of which the following is a specification.

This invention relates to the construction 10 of rolls for perforating and ribbing sheets of metal and other comparatively non-resilient material, and its object is to provide rolls of this character with readily removable perforating and ribbing dies which may be 15 removed and replaced at little expense in labor and material.

This invention consists in a pair of rolls having circumferential and longitudinal grooves, rings of perforating dies seated in 20 the circumferential grooves and ribbing dies seated in the longitudinal grooves, the perforating dies having extensions projecting beneath the ribbing dies so as to be held in position thereby.

25 It further consists of rolls of this character having longitudinal grooves which are of dove-tail cross section, ribbing dies fitting these grooves so as to be held therein and so as to hold the perforating dies in position, 30 and disks attached to the ends of the rolls to prevent endwise movement of the ribbing dies.

It also consists of the details of construction 35 illustrated in the accompanying drawings and particularly pointed out in the claims.

In the drawings, Fig. 1 is a front elevation 40 of a machine for perforating and ribbing sheet metal, embodying a pair of my novel rolls. Fig. 2 is a plan of a portion of sheet metal perforated and ribbed by this machine. Fig. 3 is a section on the line 3—3 of Fig. 2. Fig. 4 is an end elevation and Fig. 5 is a central vertical section of a pair 45 of these improved rolls. Fig. 6 is an elevation of a ring of the perforating dies for one of the rolls and Fig. 7 is a similar view of a ring of dies for the other roll.

Similar reference characters refer to like 50 parts throughout the several views.

The sheet metal 1 shown in Figs. 2 and 3 is formed with rows of perforations 2 which are produced by central and diagonal slits and by bending the tongues 3 and 4 thus 55 formed out of the original plane of the sheet.

A rib 5 is forced up between the rows of perforations and edge flanges 6 may be bent before or during the perforating and ribbing operation.

The machine for producing these perforations and ribs is shown to comprise a bed 8 in which a shaft 9 is journaled in any desired manner and this shaft carries a pulley 10 and a spur pinion 11. A pair of pedestals carry bearings for the roll shafts 12 and 13 which are connected by the gears 14 and 15. A large gear 16 on the shaft 13 meshes with the pinion 11. Any other desired means may be employed for supporting and driving the shafts 12 and 13. A cross frame 17 carries the guide plates 19 and 20 shown in Fig. 4, between which the sheets of metal are slid to the rolls and these plates prevent these sheets from twisting and buckling.

On the shafts 12 and 13 are secured the 75 rolls 21 and 22 which are formed with circumferential grooves 23 and longitudinal grooves 24. These rolls may be interchanged, but I have shown the square-topped dies 25 mounted in the grooves in the upper 80 roll and the sharp-toothed dies 26 in the grooves in the lower roll.

These perforating dies are preferably formed from rings of tool steel and after 85 being finished to the desired cross section are milled transversely to form the grooves 27 for the ribbing dies by which they are held in the circumferential grooves in the rolls. At the bottoms of the grooves 27 are the small notches 28. After these rings of 90 dies are tempered they are easily broken at these notches 28, after which they are placed in the circumferential grooves 23.

The longitudinal grooves 24 in the rolls 95 are of dove-tail cross section, as are also the bottoms of the ribbing dies 30 and 31. As the rows of these perforating dies are positioned the ribbing dies are slipped into position, extending over the extensions or feet 32 of the perforating dies and locking them in place until all the dies in both rolls are secured in position. The ribbing dies 30 are shown provided with grooves 33 and the dies 31 with ribs 33 to produce the ribs 5 on the sheet metal.

100 Disks 35 are shown secured to the ends of the roll 21 and disks 36 to the ends of the roll 22, overlapping the disks 35 but spaced therefrom sufficient to permit the flanges 6 on the sheets 1 to pass between. If desired, 110

rings 37 of hard steel may be provided to grip the sheets and hold them from shrinking because of the perforating and ribbing operations.

5. The details of construction and proportions of the parts may all be changed by those skilled in the art without departing from the spirit of my invention as set forth in the following claims.

10. I claim:—

1. In a perforating and ribbing machine, a pair of rolls having circumferential and longitudinal grooves, ribbing dies mounted in the longitudinal grooves and rings of 45 perforating dies mounted in the circumferential grooves, each perforating die embodying extensions projecting below the adjacent ribbing dies.

2. In a perforating and ribbing machine, 20 a pair of rolls having circumferential and longitudinal grooves, ribbing dies mounted in the longitudinal grooves and rings of perforating dies mounted in the circumferential grooves, each perforating die embodying 50 extensions projecting below the adjacent ribbing dies.

25. 3. In a perforating and ribbing machine, a pair of rolls having circumferential and longitudinal grooves, ribbing dies mounted in the longitudinal grooves and rings of 55 perforating dies mounted in the circumferential grooves, each perforating die embodying 60 extensions projecting below the adjacent ribbing dies, said longitudinal grooves and ribbing dies being dove-tailed in cross section.

30. 4. In a perforating and ribbing machine, a pair of rolls having circumferential and longitudinal grooves, ribbing dies mounted in the longitudinal grooves and rings of 65 perforating dies mounted in the circumferential grooves, each perforating die embodying 70 extensions projecting below the adjacent ribbing dies, the perforating dies of one roll having flat-topped outer ends and the

75. 35. perforating dies of the other roll having sharp-toothed ends, the outer ends of the perforating dies of one roll extending between the perforating dies of the other roll.

40. 4. In a perforating and ribbing machine, a pair of rolls having circumferential and longitudinal grooves, ribbing dies mounted 80

in the longitudinal grooves and rings of 45 perforating dies mounted in the circumferential grooves, each perforating die embodying extensions projecting below the adjacent ribbing dies, said longitudinal grooves and ribbing dies being dove-tailed 50 in cross section, and disks attached to the ends of the rolls to prevent endwise movement of said ribbing dies.

5. In a perforating and ribbing machine, 55 a pair of rolls having circumferential and longitudinal grooves, ribbing dies mounted in the longitudinal grooves and rings of 60 perforating dies mounted in the circumferential grooves, each perforating die embodying 65 extensions projecting below the adjacent ribbing dies, said longitudinal grooves and 70 ribbing dies being dove-tailed in cross section, and disks attached to the ends of the rolls to prevent endwise movement of said 75 ribbing dies, the disks at the ends of one roll being of larger diameter and spaced farther apart than the disks on the other roll so as to overlap them.

6. A roll formed with circumferential 70 and longitudinal grooves, the longitudinal 75 grooves having dove-tail cross sections, rings of dies mounted in the circumferential grooves, and bars slidable in the longitudinal grooves to secure the dies in position.

7. In a perforating and ribbing machine, 80 a pair of rolls formed with recesses in their faces, and ribbing and perforating dies mounted in said recesses, the perforating and ribbing dies alternating around the 85 rolls.

8. In a perforating and ribbing machine, 85 a pair of rolls embodying ribbing and perforating dies alternating around the rolls and adapted to simultaneously rib and perforate a sheet of metal passing through between the rolls.

HENRY COLLIER SMITH.
